O. JUNGGREN

ELASTIC FLUID TURBINE

Filed July 24, 1923

Inventor:
Oscar Junngren,
by *Alexander S. Hunt*,
His Attorney.

UNITED STATES PATENT OFFICE.

OSCAR JUNGGREN, OF SCHENECTADY, NEW YORK, ASSIGNEE TO GENERAL ELECTRIC COMPANY, A CORPORATION OF NEW YORK.

ELASTIC-FLUID TURBINE.

Application filed July 24, 1923. Serial No. 653,469.

To all whom it may concern:

Be it known that I, OSCAR JUNGGREN, a citizen of the United States, and a resident of Schenectady, county of Schenectady, and State of New York, have invented certain new and useful Improvements in Elastic-Fluid Turbines, of which the following is a specification.

In the construction of large elastic fluid turbines particularly those intended for use with elastic fluids of high temperature, the problem of connecting the exhaust head or housing to the turbine shell or casing is a serious one because of the great differences in temperature which exist between the turbine shell or casing and the exhaust housing, which cause unequal expansion of the parts. Particularly is this true where the casing is made of steel and the exhaust head of cast iron because of the difference in the co-efficients of expansion of steel and cast iron, and also where the elastic fluid is re-heated between stages because of the higher temperature to which the low pressure end of the casing is then subjected. For example, in some instances there may be a decrease in temperature of as much as 650° F. in a very short distance, which means a very substantial difference in temperature between the exhaust housing and the adjacent portion of the turbine casing.

The object of my invention is to provide an improved construction and arrangement for fastening a turbine casing to an exhaust housing, and for a consideration of what I believe to be novel and my invention, attention is directed to the accompanying description and the claims appended thereto.

In the drawing, the figure is a side elevation, partly in section of a turbine structure embodying my invention.

Referring to the drawing, 1 indicates the turbine shell or casing, 2 the head at the admission end of the machine and 3 the exhaust housing. Connected to head 2 is the admission conduit 4 and leading from exhaust housing 3 is the discharge conduit 5. The shaft of the turbine is indicated at 6, the bucket elements at 7, and the diaphragms at 8. The particular turbine illustrated is shown only by way of example and is to be taken as typical of any suitable turbine.

According to my invention, I connect the exhaust housing 3 to the shell 1 through the intermediary of an annular, axially-extending ring 9 formed integral with the shell and provided with a seat 10 on which the inner edge of the exhaust housing rests and which serves to center the exhaust housing relatively to shell 1. Ring 9 has a radially-projecting flange 11 against which the side edge of the exhaust housing is fastened by means of a ring of bolts 12.

The member 9 being in the form of a ring has great strength and rigidity, and while it is stiff enough to hold the exhaust housing and the turbine shell in axial alignment, still it has sufficient flexibility to permit the casing and exhaust housing to expand and contract relatively to each other without causing unduly large strains in the respective parts. At the same time the exhaust housing is accurately centered and firmly attached to the turbine casing. When the turbine casing expands radially, the ring permits it to go uniformly in all directions thereby keeping the parts in perfect alignment.

The annular ring 9 is advantageously attached to the casing at the end of the casing and projects axially forwardly toward the high pressure end of the machine. By this arrangement it is attached to the coolest part of the casing where the least expansion occurs and its provision does not increase the length of the machine over what it would otherwise be. Also, ring 9 is made conical, preferably, and stands in spaced relation to the low pressure end of casing 1. This leaves an annular air chamber between ring 9 and casing 1 which serves to protect ring 9 from the temperature of the adjacent portion of casing 1. By this arrangement ring 9 is maintained at a more even temperature and one substantially the same as that existing inside the exhaust housing.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. In an elastic fluid turbine, the combination of a casing, an exhaust housing which partially surrounds the low pressure end of the casing, and an axially-extending ring which connects the housing to the low pressure end of the casing, said 10 ring serving to permit relative radial expansion between the casing and housing, and serving also to connect the exhaust housing to the coolest part of the turbine casing.
- 15 2. In an elastic fluid turbine, the combination of a casing, an exhaust housing which partially surrounds the low pressure end of the casing, an axially-extending ring formed integral with the low pressure end of the casing, said ring being provided with a seat for the exhaust housing, and means for fastening the exhaust housing on said seat, said ring serving to connect the exhaust housing to the coolest portion 25 of the casing.
3. In an elastic fluid turbine, the combination of a casing, an axially-extending ring which surrounds the low pressure end of the casing and is formed integral therewith, said ring projecting toward the high pressure end of the turbine, and an ex- 30

haust housing connected to the free edge of said ring.

4. In an elastic fluid turbine, the combination of a casing, an axially-extending ring which surrounds the low pressure end of the casing and is formed integral therewith, said ring projecting toward the high pressure end of the turbine, means forming an axially-extending seat at the free 40 end of said ring, and an exhaust housing which is fastened to the free end of said ring and is centered by said seat.

5. In an elastic fluid turbine, the combination of a casing, an exhaust housing 45 which partially surrounds the low pressure end of the casing, and an axially extending ring which surrounds the low pressure end of the casing and connects the exhaust housing to the casing, said ring being located in 50 spaced relation to the casing.

6. In an elastic fluid turbine, the combination of a casing, a conical shaped ring connected to the low pressure end of the casing and extending forwardly therefrom in spaced relation to the casing, and an exhaust housing which partially surrounds the turbine casing and is connected to the free end of said ring.

In witness whereof, I have hereunto set 60 my hand this 23rd day of July, 1923.

OSCAR JUNGGREN.
